DESIGN FOR AN ICE TRAY

Ralph E. Kruck, Springfield, Mass., assignor to
Westinghouse Electric & Manufacturing Com-
pany, a corporation of Pennsylvania

Application April 3, 1935, Serial No. 56,193

Term of patent 7 years

To all whom it may concern:

Be it known that I, Ralph E. Kruck, a citizen of the United States, residing at Springfield, in the county of Hampden and State of Massachusetts, have invented a new, original, and ornamental Design for an Ice Tray, of which the following is a specification, reference being had to the accompanying drawing, constituting a part hereof.

Fig. 1 is a plan view of an ice tray showing my design; and

Fig. 2 is a front view of the ice tray shown in Fig. 1.

I claim:

The ornamental design for an ice tray substantially as shown.

In testimony whereof, I have hereunto subscribed my name this 29th day of March, 1935.

RALPH E. KRUCK.
